UNITED STATES PATENT OFFICE

ROSCOE D. CONKLIN, OF RAHWAY, NEW JERSEY, ASSIGNOR TO NATIONAL PNEUMATIC COMPANY, OF NEW YORK, N. Y., A CORPORATION OF WEST VIRGINIA

VACUUM ENGINE

Application filed April 9, 1931. Serial No. 528,742.

This invention relates in general to improvements in vacuum engines, more particularly in the differential type.

One of the objects of this invention is to provide a differential vacuum engine which is exceedingly simple in structure and of rugged form.

Another object of this invention is to provide a differential vacuum engine with automatic cushioning means for retarding the stroke of the engine for each end of its movement.

A further object of this invention involves a piston construction in which the cushioning means forms a part thereof.

A still further object of this invention is to provide cushioning means in an engine of this type which automatically resets itself for operation to cushion the engine near the end of its stroke in either direction.

A still further object of the invention is the provision of a cushioning means which automatically sets itself for cushioning the engine in the direction in which it is traveling.

These and many other objects as will appear from the following disclosure are secured by means of this invention.

This invention resides substantially in the combination, construction, arrangement and relative location of parts, all as will be set forth in greater detail hereinafter.

Referring to the drawings—

Fig. 1 is a view with some parts in vertical longitudinal cross section and others broken away of the engine of this invention;

Fig. 2 is a right hand end elevational view of the engine and its supporting means.

Fig. 3 is a diagrammatic view of a vacuum source, the engine of this invention and a control valve in the connection between the two.

Fig. 4 is a horizontal cross-sectional view through the valve employed in the system of this invention;

Fig. 5 is a vertical cross-sectional view through one of the check valves employed on the engine.

The engine comprises two cylinders, A and B united together in longitudinal align-

ment by means of a ring C. and screws for securing the parts together as shown in Fig. 1. The opposite ends of the cylinder are provided with end walls as shown. Near the center of the cylinders at the top thereof, is a longitudinal slot D. and the ring C. is likewise provided with a slot E. Each end of this cylinder construction is supported in a bracket F. which is provided with a right angle foot flange G'. The end brackets F. are provided with spaced ears H. through which you extend the longitudinal rods I. The end brackets F. are secured to any suitable support and the cylinder is held in place by the tie rods I which are secured in the ears by means of nuts. The left hand cylinder wall of cylinder A. is provided with a threaded port formed in the pipe receiving collar J. The port where it enters into the cylinder is restricted as shown at K. A similar coupling collar L. is provided for the right hand cylinder B. but in this case, the port into the cylinder is not restricted. At M. is a wall member provided with annular flanges internally threaded and with the coupling member N. which moves in the slots D. and E. The engine is coupled with the object to be operated such as a door by means of the member N.

Secured in the internally threaded flanges of the member N. are the smaller cylinders O. and P. which are likewise closed with end walls S. The end walls S. are provided with ports S' and a central flanged hole as shown. At T. and U. are pistons for the cylinders A. and B. which are secured to or formed integral with the smaller cylinders O. and P. which act as piston rods for these pistons. Suitable flexible cups T' and U' made of leather, for example, are secured to the pistons P. and U. by means of the annular members T'' and U''. These members T'' and U'' are formed with an annular recess as shown within which a suitable oil absorbing material T^a and U^a such as felt is secured. Within the smaller cylinders O. and P. are the smaller pistons G. and R. which are provided with the piston rods V. and W. in the form of tubes. The ends V and W are notched as shown at V^e and W^e. To the pistons G. and

R. are secured the leather cups V^a and W^a. These leather cups are secured in place by means of the discs having the central sleeves V^a and W^a and the annular discs V^b and 3 W^b. The discs V^b and W^b are shaped to form an annular channel in which the oil absorbing means V^c and W^c are mounted. The right hand end of cylinder B is exactly the same as the left hand end of cylinder A with the 10 sole exception that the port into cylinder B is not restricted as is the case of the port K into cylinder A. The structure of the parts carried by M is also the same on each side thereof as shown in section at the left 15 end and in elevation at the right end.

In the member M. are provided the inclined-oil channels 1 and 2 closed by means of the plugs 3 and 4. These channels 1 and 2 open into the cylinders O. and P. by means of 20 which oil may be introduced thereinto. Likewise in the member N. are the passages 5 and 5'. The passage 5 opens into cylinder P. and the other passage 5', opens into cylinder O. The passages 5 and 5' emerge at the lower 25 edge of member M and are provided with check valves 6 and 6' respectively constructed as shown in Fig. 5. Each check valve is of the ball type and of the same construction. Valve 6 is shown in detail in Fig. 5 as comprising a body having a chamber 8 closed by a plug 10 having a central bore 11 passing therethrough. The inner end of the plug 10 is provided with a conical seat 10' while the upper end of chamber 8 also forms a conical seat 8'. A ball 9 in chamber 8 may rest 30 on seat 10' to close passage 11 or on seat 8' to close passage 8^a which opens into passage 5. Chamber 8 opens to the atmosphere through the restricted passage 7 between 35 seats 8' and 10'.
40

Referring to Fig. 3, the engine is shown connected to a vacuum source 20 through a pipe 21, a way valve 22 and the pipes 24 and 25 which open into the cylinders A. and B. respectively. Valve 22 is operated by the lever 23 and is provided with the exhaust pipe 26.

The valve 22 is shown in detail in Fig. 4 to aid in understanding the operation of the 50 motor and system of this invention although the valve by itself forms no part of the invention. The valve comprises a casing having the four pipe connections 21, 24, 25 and 26 of Fig. 3. Within the casing is the movable part 22' of the valve provided with passages 22^a and 22^b and the handle 23. In position A pipes 21 and 24 are connected by passages 22^a and pipes 25 and 26 are connected by passage 22^b. In position C pipes 24 and 26 are connected by passage 22^a (indicated by dotted lines) and pipes 21 and 25 are connected by passage 22^b (indicated by dotted lines).

The operation of the engine will now be described. It will be assumed that with the

parts at the extreme left, as shown in the various figures, that the part to be operated by the engine, such as a door for example, is at the extreme left hand of its movement. In the case of a door, it will be assumed that 70 the door is closed in this position of the parts.

As is apparent from Fig. 1 and the previous description, member M and all the parts attached thereto including N, 6, 6', O, P, T and U with their attached parts form a unit and 75 move together. Pistons G and R and their attached parts including V and W are supported by that unit but move with or with respect thereto depending upon pressure conditions within the device. 80

Referring to Fig. 1 piston R. and the parts connected thereto, would normally be at the extreme left in cylinder P. that is against the member M. When valve 22 is operated to connect pipes 21 and 25, pipes 24 and 26 will 85 be connected. The vacuum source 20 is then connected to cylinder B. and cylinder A. is connected to the atmosphere. The result is that the member M. and all the parts connected thereto begin to move to the right. At 90 the same time, piston R. will begin to move to the right with respect to the moving parts. This is true, because at the same time that cylinder B. is connected with the vacuum source, cylinder P. is connected to the vacuum 95 source through the ports which correspond to the ports S' of cylinder O. Piston R. and the parts connected thereto begin to move to the right with respect to the other moving parts, ball check valve 9 will be raised off its 100 seat sufficiently to let atmospheric pressure pass through passages 11 and 5 into cylinder P. to the left of piston R.

This piston R will continue to move to the right with respect to cylinder P. until its sleeve W^a strikes the end wall of the cylinder P. This position of piston R. and its connected parts is shown in Figure 1. When all of the moving parts have moved to the right to the point where the projecting piston rod W. engages the end wall of cylinder B. piston R. will stop while all of the other moving parts of the engine will continue in their movement to the right. As a result the air in cylinder P. behind piston R. is trapped 115 since the ball 9 will fall back on its seat to close passage 11. The trapped air can then only escape from cylinder P. through passages 5 and 8^a and the restricted port 7. The result is that for the remainder of the stroke 120 of the main parts of the engine, they will be cushioned and slowed down in their movement so that the engine will approach the end of the stroke at a reduced speed.

To effect the operation of the parts in the 125 opposite direction, that is to the left in the figures, valve 22 is operated to connect pipes 21 and 24 and 25 and 26. The operation of the engine will then be substantially the same except that all of the parts will move more 130

slowly to the left because of the restricted port K. In this case piston G. and its connected parts will move to the left within cylinder O. because the vacuum source which is connected to cylinder A. is also connected to the interior of cylinder O. through the ports S'. The other check valve with the ball 9 which is now shown, will permit atmospheric pressure to enter cylinder O. behind piston G.

The operations are the same as previously described, except as stated, the parts will move more slowly in the opposite direction which, in the case of a door, would be door closing direction.

It will be apparent from the above disclosure that this invention resides in certain principles of construction and operation which may be embodied in other physical forms and carried out in other ways without departure therefrom, and I do not, therefore, desire to be strictly limited to the disclosure as given for purposes of illustration, but rather to the scope of the appended claims.

25 What I seek to secure by United States Letters Patent is:

1. In a vacuum engine of the type described, the combination comprising a cylinder, two pistons mounted in said cylinder, hollow piston rods uniting said pistons, means to separate the hollow piston rods into two chambers, pistons mounted solely in the chambers, and valve means for permitting the introduction of air into said chambers behind the pistons.

2. An engine of the type described, comprising a cylinder having ports at each end, said cylinder having an opening intermediate its ends, pistons in said cylinder, hollow piston rods uniting said pistons in a rigid unit, means to separate the hollow piston rods into two chambers, pistons in said chambers having piston rods movable to the exterior thereof, and check valves controlling passages opening into the piston rod chambers.

3. A vacuum engine of the type described, comprising a cylinder closed at both ends and provided with a port at each end, said cylinder being open intermediate its ends, two pistons in said cylinder, a hollow piston rod connecting said pistons into a rigid unit, means for dividing the hollow piston rod into separate chambers, a piston in each of said chambers, each having a piston rod, each chamber having a passage connecting it with the atmosphere, and a ball check valve in said passage.

4. A vacuum engine of the type described, comprising a cylinder closed at both ends and provided with a port at each end, said cylinder being open intermediate its ends, two pistons in said cylinder, a hollow piston rod connecting said pistons into a rigid unit and divided into separate chambers, a piston in each of said chambers, each having a piston

rod, each chamber having a passage connecting it with the atmosphere, and a ball check valve in said passage, each of said valves having a restricted by-pass.

5. An engine of the type described, comprising a cylinder closed at each end and provided with a port, by means of which the cylinder may be alternately connected to a vacuum source, said cylinder being open intermediate its ends, pistons in said cylinder, a hollow piston rod uniting the pistons in a rigid unit and forming substantially closed chambers having end walls, each of the pistons in said chambers having a piston rod slidable through an opening in the end wall of the closed chamber, and ball check valves controlling a passage opening into said chambers behind the pistons therein.

6. An engine of the type described, comprising a closed cylinder having a port at each end and having an opening intermediate its ends, two pistons in said cylinder, two smaller cylinders united at their inner ends by a coupling member, said smaller cylinders having walls at their other ends with central openings and said pistons mounted one on each smaller cylinder, pistons in said smaller cylinders having piston rods slidable through the central openings of the end walls, two passages in said coupling member, one opening into one of the smaller cylinders and the other opening into the other of the smaller cylinders, and check valves mounted on said coupling member for controlling said passages.

7. An engine of the type described, comprising a closed cylinder having a port at each end and having an opening intermediate its ends, two pistons in said cylinder, two smaller cylinders united at their inner ends by a coupling member, said smaller cylinders having walls at their other ends with central openings, and said pistons secured one to each smaller cylinder, pistons in said smaller cylinders having piston rods slidable through the central openings of the end walls, two passages in said coupling member, one opening into one of the smaller cylinders and the other opening into the other of the smaller cylinders, and ball check valves mounted on said coupling member for controlling said passages, each of said ball check valves having a restricted by-pass connecting the passages with the atmosphere between the ball check valves and the spaces within the small cylinders.

8. An engine of the types described, comprising a closed cylinder having a port at each end and having an opening intermediate its ends, two pistons in said cylinder, two smaller cylinders united at their inner ends by a coupling member, said smaller cylinders having walls at their other ends with central openings and having said pistons attached thereto, pistons in said smaller cylinders

ders having piston rods slidable through the central openings of the end walls, two passages in said coupling member, one opening into one of the smaller cylinders and the other opening into the other of the smaller cylinder, and ball check valves mounted on said coupling member for controlling said passages, said ball check valves being unseated by atmospheric pressure to supply atmospheric pressure into the small cylinders when unseated.

9. A vacuum engine as described comprising two connected cylinders, connected pistons within said cylinders, cushioning means mounted on said pistons operable to cushioning position in the direction of movement of the piston initially upon connection to the vacuum source and means for supplying air at atmospheric pressure to the cushioning means initially upon connection to the vacuum source.

In testimony whereof I have hereunto set my hand on this 7th day of April A. D., 1931.

ROSCOE D. CONKLIN.
